Primary Examiner — Keli L Hill(74) *Attorney, Agent, or Firm* — Knobbe, Martens, Olson & Bear, LLP(57) **CLAIM**

The ornamental design for a video game controller, as shown and described herein.

DESCRIPTION

FIG. 1 is a top, front perspective view of a video game controller;

FIG. 2 is a top plan view thereof;

FIG. 3 is a bottom plan view thereof;

FIG. 4 is a left-side elevation view thereof;

FIG. 5 is a right-side elevation view thereof;

FIG. 6 is a front elevation view thereof; and,

FIG. 7 is a rear elevation view thereof.

The broken lines shown are included for the purpose of illustrating portions of the video game controller that form no part of the claim.

1 Claim, 7 Drawing Sheets(56)
